UNITED STATES PATENT OFFICE.

HERBERT E. WHITE, OF YOUNGSTOWN, OHIO.

APPARATUS FOR EXPANDING SLITTED METAL.

No. 895,923.

Specification of Letters Patent.

Patented Aug. 11, 1908.

Application filed February 5, 1908. Serial No. 414,426.

To all whom it may concern:

Be it known that I, HERBERT E. WHITE, of Youngstown, in the county of Mahoning and State of Ohio, have invented a new and useful Improvement in Apparatus for Expanding Slitted Metal, of which the following is a full, clear, and exact description, reference being had to the accompanying drawings forming part of this specification, in which—
10. Figure 1 is a side elevation, showing expanding apparatus constructed in accordance with my invention; Fig. 2 is a plan view of the dies proper with the top rolls removed; Fig. 3 is an enlarged side elevation or face view of one of the dies, partly broken away, showing the expanding steps or shoulders; Fig. 4 is a plan view of the slitted blank in its preferred form; and Fig. 5 is a partial plan view partly in section showing more clearly 20 the steps in the dies.

My invention relates to apparatus for expanding slitted metal sheets, and is designed to provide a simple and effective apparatus for this purpose, in which the expanding action may be obtained without the use of moving parts.

To that end, the invention consists in providing a pair of coacting dies between which the metal is forced or drawn, said dies having 30 coacting stepped inclines which bend the successive cut strands away from their original plane and deflect the sheet, as a whole, into a new plane during this action. In the use of the apparatus, the previously slitted sheet 35 is fed thereto, so that the only action in the apparatus is that of bending and expanding the metal.

In the drawings, 2 and 3 are the dies which, in this form, are shown as having their operating faces extending vertically, though, of course, they may be set with these faces in any desired plane. Each inner die face is formed with a series of inclined steps 4, extending forwardly and downwardly at a general angle which is determined by the amount of expansion desired. These inclined steps or shoulders are preferably slightly curved, as at 4^a, so that the bending operation does not take place entirely at the upper ends, the metal being gradually expanded as the uncut portions between the slits move forwardly and downwardly along the die shoulders. The shoulders on one of the dies are extended above those on the other sufficiently to engage the uncut portions between the slits, and the width of the shoulders is determined by

the width of the strands. The space between the dies is fixed according to the width of the strands. The dies may be secured at the proper distance apart by any suitable means, 60 and for this purpose I have shown bolts 5, 5 at each end, which secure the dies together. These bolts preferably extend through slots at the thinner end of each die, so that the dies may be shifted longitudinally of each other to 65 provide more or less clearance, according to the thickness of the metal being expanded. The dies are cut or formed to operate upon a certain length of slit and a certain width of strand, different dies being employed for different widths of strands and different lengths of slits. The horizontal distance from the upper end of one shoulder or rib on the die to the upper end of the next shoulder or rib is fixed by the length of the slits, being equal to 70 one-half the distance from center to center of the uncut portions at the ends of each slit.

Any desirable means may be provided for feeding the sheet through the drawing dies. In the present case, I have shown pairs of 80 pinch or feed rollers 6, 7, which are of successively different lengths, the lower set being mounted in suitable recesses in one die, while the upper set is mounted in plates or housings 8, which are secured to the two dies. 85 The bearings for one set of the rollers are preferably made adjustable so as to adjust the pressure upon the sheet, and the rollers may be driven in any desirable manner, as, for example, by connecting the shafts by spur 90 gears 9, one set of shafts being also provided with bevel gear connections 10, to a line shaft 11, driven from any suitable source of power. These rollers are rotated in a direction proper to feed the slitted sheet forwardly against the 95 upwardly projecting points engaging the successive uncut portions, so that as the sheet feeds forwardly, these portions travel downwardly between the two sets of inclines, thus gradually expanding the metal and forming 100 the meshes. These feed rollers will carry the sheet forwardly through the dies, the sheet being thus deflected into a different plane as it is expanded. The sheet will pass out in a downwardly and forwardly inclined direction, and in order to draw out the last end portion of the sheet, I preferably employ inclined rollers 12, which are preferably driven by a belt or some other connection which will allow some slip between them and the metal. 105 These rollers engage the edge portions of the expanded mesh strands, and will pull or draw

the last portion of the sheet through the expanding apparatus.

As the sheet begins to feed through the dies the dies first operate upon one corner of the sheet and successively expand a greater number of strands until the full width of the sheet is reached. As the last portion of the sheet feeds through the machine, the number of meshes acted upon successively decreases until the diagonally opposite corner to that starting in is expanded in the last portion of the travel.

In the use of the apparatus, it will preferably be employed as part of an organized machine, the metal sheets being fed to slitting rollers in front of the expanding apparatus, and the sheet being then fed forward from the slitting rollers or other slitting apparatus into and through the expanding apparatus.

If the metal is slit in the ordinary way with a continuous strand along that edge which first engages the dies, the set of meshes at this edge of the product will be of slightly different shape from that of the remaining meshes. To overcome this slight difference, I preferably cut away one set of strands between the neck portions to this edge, leaving the portions 13, as shown in Fig. 4. This, however, may or may not be used, as desired, as its only purpose is to make all meshes uniform throughout the sheet. This cutting of the strands may be carried out during the slitting operation and by the same dies or rollers.

The advantages of my invention result from the simplicity and effectiveness of the dies. No moving parts are necessary, the expanding operation being carried out by the coacting inclined steps of the two dies acting upon the uncut portions. The same dies may be employed for different thicknesses of sheets, and may be easily replaced by corresponding dies, to arrange the machine for different widths of strands and different lengths of slits. Owing to the fact that the expanding operation is entirely separate from and takes place after the slitting operation, there is no complication between the two operations, as they are separate and independent. The apparatus gives a uniformity of mesh throughout the product, and owing to the change in angle of the steps, the expanding operation is gradual, so that the resistance is uniform throughout the bending of the strands.

While I have shown the horizontal distance from the upper end of one shoulder or step on the die to the upper end of the next shoulder or step as being equal to one-half the distance from center to center of the uncut portions at the end of each slit in the metal, I may use half the number of steps, and make the distance between them equal to the distance from center to center of the uncut portions.

Many other changes may be made in the form and arrangement of the dies and their steps, as well as in the means for feeding the sheets therethrough, without departing from my invention, since I consider myself the first to employ two-stepped dies between which the metal is drawn and in which the expanding operation takes place.

I claim:

1. In apparatus for expanding slitted metal sheets, a pair of stationary co-acting dies, at least one of which has a series of inclined steps; substantially as described.

2. In apparatus for expanding slitted metal sheets, a pair of stationary co-acting dies, said dies having each a series of inclined steps on its inner face; substantially as described.

3. In apparatus for expanding slitted metal sheets, a pair of stationary co-acting dies, said dies having each a series of inclined steps on its inner face, together with means other than and in addition to the dies for forcing the metal to be expanded between the dies; substantially as described.

4. In apparatus for expanding metal sheets, a pair of stationary co-acting dies arranged side by side with a space between them, the inner face of at least one of said dies having a plurality of inclined steps; substantially as described.

5. In metal expanding apparatus, an expanding die having upon one face thereof a plurality of steps extending obliquely thereof in a transverse direction; substantially as described.

6. In apparatus for expanding slitted sheets, a pair of dies having inclined steps, the distance between the upper die points of one die being substantially equal to half the distance from one uncut portion to the next uncut portion; substantially as described.

7. In metal expanding apparatus, an expanding die, having upon one face thereof a plurality of oblique transverse steps or shoulders, said steps or shoulders being in stepped relation to each other longitudinally of the die; substantially as described.

8. In apparatus for expanding slitted sheets, a pair of dies having coacting stepped inclines, and feed rollers arranged to force the slitted metal forwardly between the dies, substantially as described.

9. In apparatus for expanding slitted sheets, a pair of dies having coacting inclined steps, and draw-out mechanism arranged to pull out the last portion of the sheet, substantially as described.

10. In apparatus for expanding slitted sheets, a pair of relatively fixed dies adjustably spaced with reference to each other, having substantially parallel coacting inclined steps, substantially as described.

11. In apparatus for expanding slitted sheets, a pair of relatively fixed dies having

coacting inclined steps in spaced relation to each other, and a series of feed rollers for forcing the sheet between said dies, substantially as described.

- 5 12. In apparatus for expanding slitted sheets, a pair of relatively fixed dies spaced from each other and having their adjacent faces formed with coöperating inclined steps, substantially as described.
- 10 13. In apparatus for expanding slitted sheets, a pair of dies in spaced relation to each other, and having their adjacent faces formed with parallel inclined curved steps, substantially as described.

14. In apparatus for expanding slitted sheets, a pair of relatively fixed dies, at least one of which has its working face formed with a series of inclined steps, a series of feed rollers journaled in recesses in one of the dies, and a second coacting series of rollers journaled adjacent to those of the first named series, substantially as described.

In testimony whereof, I have hereunto set my hand.

HERBERT E. WHITE.
